BURIAL VAULT SEAL

Andrew F. Holz, Bristol, Conn.

Application January 8, 1935, Serial No. 892

5 Claims. (Cl. 72—7)

This invention relates to mausoleums or burial vaults and also to the method of sealing the opening of the vault.

My invention contemplates the use of a burial vault simulating a full sided house having a suitable opening in a wall thereof. This type of burial vault has not been extensively used in the past due to the difficulty of providing a satisfactory seal around the closure. This difficulty is primarily due to the fact that such an opening is necessarily within a vertical wall and therefore presents many difficulties in the application of the sealing medium.

In accordance with the above it is the primary object of my invention to provide in a burial vault a particularly effective seal for a door or other opening thereof, the application of which will not require the use of any tools or other equipment.

A further object of my invention is to provide a novel and improved method for the sealing of burial vault doors by which the interior of the vault is more securely hermetically sealed against dampness and other such elements of the atmosphere which induce decay or decomposition.

The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therein as do not affect the spirit of the invention nor exceed the scope thereof as expressed in the appended claims.

In the drawing:

Fig. 1 is an elevational view of the door end of my burial vault.

Fig. 2 is a side elevational view, partly in central section, of the vault shown in Fig. 1; and

Fig. 3 is a perspective view of the door placement clamp.

Referring now to the drawing for a more detailed description thereof, the numeral 4 indicates a full-sided burial vault which, in the preferred form as illustrated, is constructed of a homogeneous mass of water-proof concrete or other suitable masonry material. The burial vault 4 comprises a gable roof 5, integrally formed vertical walls 6, a rear end wall 7 and a front end wall 8, all of the vertical walls being integrally formed with a base or floor structure 9.

In the preferred embodiment of my invention a door opening 10 is formed in the end wall 8 of the vault. It is however obvious that it may be desirable to form the opening 10 in any of the vertical walls of the vault. To provide a closure for the vault a door 11 is placed within the opening 10. The periphery of the door 11 near its outer surface is stepped or rabbeted, as indicated at 12, so as to fit snugly in a similar formation in the periphery of the opening 10 by which a positive stop for the installation of the door 11 is provided. The inner portion of the periphery of door 11 indicated by numeral 13 is provided with a plurality of grooves 14 which extend continuously around the door and are in juxtaposition with similar grooves 15 formed in the door jamb. The grooves 15 also extend entirely around the door jamb. A plurality of ports 16 formed within the door 11 are situated at various elevations and extend from the grooves 14 outwardly to terminate in the front surface of the door.

The purpose of the grooves 14 and 15 is to more thoroughly effect an air-tight seal for the door when a suitable sealing compound, such as pitch, is poured therein. To provide a particularly desirable means by which the sealing compound may be effectively applied to the space between the door 11 and the door jamb, the reservoir 17 is provided in the region above the door opening 10. In the preferred form of my invention the reservoir 17 is formed and constructed within the end wall 8 and is provided at its lower surface with an aperture 18 communicating via the door jamb to the grooves 14 and 15. The upper portion of the reservoir 17 communicates to the outside air thru an aperture 19. A stopper 20 is placed in the aperture 18 and has attached to it a cord 21 which extends upwardly thru the port 19 and terminates outside the vault in a ring 22.

At each side of the door opening 10 and secured to the vault structure is a pair of U-shaped loops 24 which, in conjunction with a clamp, provides means by which the door is pushed tightly into position within the door opening 10. The just mentioned door placement clamp is illustrated in perspective in Fig. 3 and comprises a cross bar 25, the ends of which are adapted to engage in the loops 24, and a clamp screw 26 threadedly engaged with the bar 25. Screw 26 is provided at one end with an operating handle 27, the other end being equipped with a circular shoe 28 swivelly mounted on the screw. After the placement of the door 11 approximately within the

opening, the bar 25 has its ends engaged in the loops 24, after which the screw handle 27 is rotated so that the shoe 28 contacts with the door and forces same tightly against the door jamb shoulders 12.

The door 11 having been properly installed in place as just described, it is now in readiness for the application of the sealing compound by which the joint between the door and jamb is hermetically sealed to shut out all the atmospheric elements. Within the reservoir 17 has been placed a sufficient quantity of sealing compound, such as pitch, the stopper 20 having been previously placed in the aperture 18. When the door is ready for sealing, the stopper 20 is removed by pulling on the cord 21. The sealing compound is thus permitted to run down into the grooves 14 and 15 until the entire space bordering the periphery of the door 11 is filled with the sealing compound. The ports 16 function to indicate that the sealing compound has reached the various levels at which the ports 16 are located in that the compound will appear at each of these levels to indicate this condition. The sealing compound used in conjunction with my invention is of such composition as to congeal immediately upon being exposed to the atmosphere so that as the compound reaches the exposed portions of the crevices and also the terminals of the ports 16 it will congeal there and prevent any waste of the compound.

It is obvious that my method of sealing the closure door, as illustrated in the drawing and described herein, may be employed during or immediately proceeding the usual interment ceremonies in that the execution of the sealing process is not visible to the casual observer and therefore possesses the desired characteristics so necessary at such functions. It may also be observed that a positive seal is assured as evidenced by the sealing compound appearing at each of the ports 16.

What is claimed as new and useful is:

1. The method of sealing a burial vault door, which comprises forming a groove in the perimeter of the door, forming in the structure adjacent the door an internal perimetral groove opposite the groove in the door, forming a reservoir having passageway extending from the exterior of the mausoleum to said groove so that sealing material may pass thru said passageway into

said groove, placing a removable stopper in the lower part of said passageway, putting sealing material in the passageway above said stopper, and removing the latter to allow the sealing material to pass into said groove and fill the same. 5

2. The method of sealing a burial vault door, which comprises forming a groove in the perimeter of the door, forming in the structure adjacent the door an internal perimetral groove opposite the groove in the door, forming a passageway extending from the exterior of the mausoleum to said groove so that sealing material may pass thru said passageway into said groove, forming a vertical series of indicating openings communicating with said groove and extending to the front surface of the door, placing a removable stopper in the lower part of said passageway, putting sealing material in the passageway above said stopper, and removing the latter to allow the sealing material to pass into said groove and fill the same. 10

3. A burial vault having an opening in its vertical wall and comprising a closure fitted into said opening, continuous grooves in abutting surfaces of the respective closure and opening, a reservoir above said opening and having a passageway leading to said groove whereby a sealing compound in said reservoir may be delivered to said groove to seal the closure. 15

4. A burial vault having an opening in its vertical wall and comprising a closure fitted into said opening, continuous grooves in abutting surfaces of the respective closure and opening within the wall of said vault, a reservoir above said opening and having a passageway leading to said groove whereby a sealing compound in said reservoir may be delivered to said groove to seal the closure. 20

5. A burial vault having an opening in its vertical wall and comprising a closure fitted into said opening, continuous grooves in abutting surfaces of the respective closure and opening, a vertical series of indicating apertures communicating with said groove and extending to the front surface of said closure, a reservoir above said opening and having a passageway leading to said groove whereby a sealing compound in said reservoir may be delivered to said groove to seal the closure. 25 45 50
